[57] CLAIM

The ornamental design for a combined automotive electrical testing module and holder/display therefor, as shown and described.

DESCRIPTION

FIG. 1 is a front elevational view of a combined automotive electrical testing module and holder/display therefor, showing our new design;

FIG. 2 is a right side elevational view, the broken-line showing being environmental only and forming no part of the claimed design;

FIG. 3 is a top plan view;

FIG. 4 is a rear elevational view;

FIG. 5 is a left side elevational view;

FIG. 6 is a bottom plan view;

FIG. 7 is a front elevational view of the module portion of FIG. 1, the remainder being omitted for ease of illustration;

FIG. 8 is a rear elevational view of FIG. 7;

FIG. 9 is a left side elevational view of FIG. 7;

FIG. 10 is a right side elevational view of FIG. 7;

FIG. 11 is a top plan view of FIG. 7;

FIG. 12 is a bottom plan view of FIG. 7;

FIG. 13 is a front elevational view of FIG. 1, with the module portion omitted for ease of illustration;

FIG. 14 is a right side elevational view of FIG. 13, the broken-line showing being environmental only and forming no part of the claimed design;

FIG. 15 is a top plan view of FIG. 13;

FIG. 16 is a rear elevational view of FIG. 13;

FIG. 17 is a left side elevational view of FIG. 13; and

FIG. 18 is a bottom plan view of FIG. 13 thereof.
